HOT AIR FURNACE

James O. Johnston, St. Petersburg, Fla., assignor
to City Fuel Oil and Coal Company, St. Peters-
burg, Fla., a corporation of Florida

Application July 24, 1940, Serial No. 347,315

2 Claims. (Cl. 126—110)

This invention relates generally to hot air furnaces; and more particularly to compact air-heating units adapted to heat and discharge warm filtered air directly into small houses or apartments.

The main object of the invention is to provide a compact heater of great efficiency in comparison to its size and of such simplicity in construction as to adapt it for manufacture and installation at low cost.

Other objects of the invention will become apparent as the detailed description thereof proceeds.

In the drawings:

Fig. 1 is a vertical section of the hot air heater forming the subject matter of this application, the section being taken on the line 1—1 of Fig. 2;

Fig. 2 is a central vertical section taken substantially on the line 2—2 of Fig. 1, some of the lower parts being shown in elevation;

Fig. 3 is a horizontal section taken on the line 3—3 of Fig. 2;

Fig. 4 is a horizontal section taken on the line 4—4 of Fig. 2; and

Fig. 5 is a fragmentary vertical section taken on the line 5—5 of Fig. 4.

As shown in the drawings, this air conditioner comprises a casing of suitable sheet material, designated generally by the reference numeral 6. Angle iron standards 7, suitably cross connected to each other form the supporting framework for the casing and the other members of the furnace. The front wall 8 of the casing is cut to form a circular aperture 9 in which a closure plate 10 fits snugly to form a mount for the burner 11, the specific details of which form no part of the present invention.

A cylindrical heating chamber or primary heat exchanger 12, of substantially the same diameter as the aperture 9, is suitably secured with gas-tight fit to the front wall 8, and extends horizontally from said aperture toward the rear wall 13 of the casing. The rear end of the chamber 12 is closed by a plate 14 and is spaced from the wall 13 to form an air conducting passageway 15. A strap 16 has its opposite ends bent to form the legs 17 and 18 and is secured to the plate 14 with the ends of the legs 17 and 18 sprung into the corners of the adjacent angle iron standards 7 of the framework.

As shown clearly in Figs. 1 and 2, the heating chamber 12 has its cylindrical outer surface spaced inwardly from the side walls 19 and 20 of the casing 6, in order to form, along with the passageway 15, symmetrically arranged conduits

for air directed from the lower end of the casing against the said chamber 12. A frusto-pyramidal partition or lower deflector members 21 is arranged in the casing directly below the chamber 12, and is provided with a flanged aperture 22 adapted to be connected by a flexible connector 23 to the discharge outlet 24 of a blower 25. The partition 21 forms the top of a chamber 26 in which the blower 25 is mounted for operation by the motor 27. In order to reduce vibration to a minimum, the blower supporting standards 28 and 29 are mounted at their lower ends on springy straps 30 and 31, respectively, which extend across the casing 6 between the walls 19 and 29. The opposite ends of these straps are secured to vibration dampeners 32 supported by shelves 33 projecting inwardly from the framework of the furnace.

The standard 29 includes a pair of uprights 34 and 35 extending vertically up from the strap 31. A cross-bar 36 connects the tops of the uprights 34 and 35 and carries a bearing at its center to support one end of the blower axle 38. The structural details of the standard 28 are not shown in the drawings, since they are the same as the details of the standard 29. The axle 38 projects beyond the blower supporting standard 28 to receive a pulley 39 connected for rotation by a belt 40 driven by the motor 27, which is also suitably mounted on the straps 30 and 31 to reduce vibration as much as possible. An air filter 41, detachably mounted on angle irons 42, closes the bottom of the blower chamber 26.

A short flue 43 connects the primary heating chamber 12 to a secondary heat exchanger or heater 44; and a discharge flue 45 extends from the upper end of the heater 44 through the front wall 8 of the furnace casing. A flange 45' on the outer end of the flue 45 is adapted to connect to such piping as may be found necessary to conduct the products of combustion away from the rooms or apartments being heated by the furnace.

As shown in Figs. 2 and 4, the secondary heater 44 is supported by the flues 43 and 45, with its top, bottom and side walls spaced apart from the adjacent parts of the casing 6 and primary heating chamber 12 in order to ensure a secondary heating of the air previously heated by contact with the surface of the chamber 12. To increase the air heating surface area of the secondary heater 44, pipes 48 and 49 extend through the top 50 and bottom 51 of the heater 44 and form additional heating passageways for the air previously heated by chamber 12. Any desired

number of these pipes may be used to superheat the air as it is forced upwardly around and across the primary heater 12 toward the register formed by the apertured top 41 of the furnace casing. In order to deflect the air flowing past the primary heater 12 inwardly across the bottom 51 of the secondary heater 44 and around the pipe 43, angular baffles or upper deflector members 52 and 53 are secured to the sides 19 and 20 of the furnace casing to project inwardly between the top of primary heater 12 and secondary heater 44.

When the burner 11 is ignited, the air within the chamber 12 becomes heated and, with the products of combustion, escapes through the short pipe 43 into the secondary heater 44 and around the pipes 48 and 49 to the discharge flue 45 and its connector 45'. The air drawn through the filter 41 by the blower 25 is forced around and across the primary heater 12 and across the bottom of the secondary heater 44 by the baffles 52 and 53 to be superheated by contact with the hot surfaces of the heater 44 and pipes 48 and 49 as it flows or is forced toward the register 47.

While the top, bottom and sides of the furnace casing 6 are illustrated as integrally connected to each other, it will be readily understood that these members may be detachably connected to each other and provided with whatever means may be found necessary or desirable to facilitate assembly, or provide access to the various parts for repair or renewal.

What I claim is:

1. In a hot air furnace of the type comprising an open lower end and a top apertured to form a register, a cylindrical combustion chamber extending horizontally as a primary heat exchanger, a blower adapted to direct a flow of air about the said primary heat exchanger, a secondary heat exchanger mounted vertically above the said primary heat exchanger and the said secondary heat exchanger having openings extending vertically through the said secondary heat exchanger toward the said register; the improvement which comprises an inverted frusto-pyramidal partition dividing the said furnace into upper and lower chambers and having an air inlet at its downwardly directed apex and with the outlet of the said blower coincident with said inlet, and the said inverted frusto-pyramidal partition positioned in such a manner as to direct the air from the said blower around the lower surface of the said primary heat exchanger and around the end of the said

cylindrical primary heat exchanger, deflector members projecting into the space between the said primary and secondary heat exchanger, the said deflector members adapted to cooperate with the said frusto-pyramidal partition in such a manner as to direct the said flowing air circumferentially around opposite semi-circular surfaces of the said cylindrical combustion chamber, each of the said deflector members having an upper and lower side and the said lower side connected substantially at an angle to the said upper side whereby the flowing air from the blower aforesaid is retarded and directed by the lower side of the said deflector members around the upper surface of the primary heat exchanger and a portion of the said flowing air is directed by the said lower side along the bottom wall of the secondary heat exchanger toward the lower ends of the aforementioned openings provided in the said secondary heat exchanger and whereby the remaining portion of the said flowing air is directed by the said upper side of the said deflector members around the said secondary heat exchanger toward the said register.

2. In a hot air furnace of the type comprising an open lower end and a top apertured to form a register, a cylindrical combustion chamber extending horizontally as a primary heat exchanger, a blower adapted to direct a flow of air about the said primary heat exchanger, a secondary heat exchanger mounted vertically above the said primary heat exchanger and the said secondary heat exchanger having openings extending vertically through the said secondary heat exchanger toward the said register; the improvement which comprises lower deflector members adapted to direct the air from the said blower around the lower surface of the said primary heat exchanger, upper deflector members projecting into the space between the said primary and secondary heat exchanger, the said upper and lower deflector members adapted to direct the said flowing air from the said blower circumferentially around opposite semi-circular surfaces of the said cylindrical combustion chamber and the upper deflector members positioned in such a manner as to retard the flowing air from the blower aforesaid and direct the said flowing air toward the lower ends of the said openings provided in the said secondary heat exchanger and toward the said register.

JAMES O. JOHNSTON.
